UNITED STATES PATENT OFFICE.

PERCIVAL R. TEMPLE, OF EVERETT, AND GEORGE W. PIERCE, OF BOSTON,
MASSACHUSETTS, ASSIGNORS TO THE YALE LOCK MANUFACTURING
COMPANY, OF STAMFORD, CONNECTICUT.

POST-OFFICE BOX.

SPECIFICATION forming part of Letters Patent No. 252,154, dated January 10, 1882.

Application filed April 30, 1881. (No model.)

To all whom it may concern:

Be it known that we, PERCIVAL R. TEMPLE, of Everett, in the county of Middlesex, and GEO. WILLIS PIERCE, of Boston, county of 5 Suffolk, both in the State of Massachusetts, have invented certain Improvements in Post-Office Letter-Boxes, of which the following is a specification.

Our invention relates to post-office letter-10 box systems, and has for its object to provide for a new system of receiving mail-matter and for delivering it.

In the system now generally in use fixed 15 boxes or pigeon-holes are arranged in tiers of any desired number, each box having on the outside, accessible to the subscriber or box-owner, a door with a suitable lock, the key of which is held by the subscriber. The opposite end of the box is open for the post-office 20 clerk's convenience in placing within it the proper mail.

While this system possesses many desirable 25 features, it still has some serious defects incident to it—first, that of lack of safety. While to a certain extent there is safety in the locks usually upon such boxes, the element of danger lies in the fact that while on the way to or from the post-office a dishonest employé has the opportunity to abstract valuable letters, 30 and unless registered all trace of them is lost. Again, there is lack of privacy in such carriage of mail, because there is usually no provision by a large class of subscribers of any receptacle whatever in which to carry the mail 35 to or from the post-office, and even where mail-bags are used, as is sometimes the case, they are open to the inspection of the carriers, and to whomsoever they may choose to exhibit them.

40 Our invention seeks to remove these objections; and it consists of certain appliances whereby the security and privacy of mail-matter are greatly increased, both for conveyance to post-offices and to box-subscribers' places of business.

We propose a new system, contemplating the use of portable supplemental mail lock-boxes, into which the mail can be as readily

distributed as in the present fixed boxes, and by means of which the contents can be transferred to the hands of the box-subscribers without the carriers seeing them or having an opportunity of securing any part of them, except by resorting to such means as would probably involve their detection. Mail-matter can also 55 be placed securely in these portable lock-boxes by box-subscribers at their offices, and thus delivered into the hands of carriers and be conveyed to the post-office clerks without the contents of the boxes being seen or disturbed 60 by the carriers.

In the accompanying drawings, Figure 1 represents a front view in perspective of four post-office boxes, according to our invention, secured in pigeon-holes. Fig. 2 represents a 65 rear view of the same. Fig. 3 represents a horizontal section through two such boxes, one in its normal position, the other partially withdrawn from its pigeon-hole. Fig. 4 shows the rear end of a box with its door closed. 70 Fig. 5 represents a horizontal section of the rear end of the box, showing the position of the parts when the box is partially withdrawn from the pigeon-hole. Fig. 6 shows a similar view with the box less withdrawn. Fig. 7 75 shows a horizontal section of the box in its normal position within a pigeon-hole. Fig. 8 represents devices for the reception of mail at the post-office in accordance with our system of deposit and delivery. Figs. 9, 10, 11, and 80 12 show constructions by which a metallic box-front or a continuous metallic frontage is secured.

A indicates portable mail-boxes, made of any suitable material, preferably of metal, arranged 85 to slide into and out of pigeon-holes. The outer end, a, of each box is solid, and has a handle, a', by which the box is placed into and withdrawn from the pigeon-hole, and by means of which the box may be carried in the hand 90 of the carrier to and from the post-office. In the end a is a suitable lock, a², of any desired pattern, (not shown in detail,) by which the box is fastened to the upper side of the pigeon-hole wall, to prevent its being withdrawn by any 95 one except the carrier or key-holder. The op-

posite end, *b*, of the box has a hinged door, *c*, having a spring-lock, *l*, to which are two keys, one in care of the post-office clerk and the other in possession of the box-subscriber. When the 5 box is placed in the pigeon-hole the door *c* is closed, and afterward can be unlocked and opened by the post-office clerk, as shown in the lower part of Fig. 2.

Upon the door at the hinge end is a projection or boss, *g*, having a cavity, *g'*, within which is a coil-spring, *s*, arranged to bear against the long arm of bell-crank lever *t*, whose short arm *t'* normally rests upon the abutment *t''*. The door is held to the box by means of the rod *p*, passing through the lugs *m* of the box and *n* of the door, and also through the bell-crank lever *t*, as shown. The lever *t* is so arranged that when the door is open, as shown in Fig. 7, it prevents the door from being thrown open 15 fully, so as to obstruct the opening of the adjacent box.

The details of construction above described may obviously be modified without departing from the substance of our invention.

25 There should be, in connection with each pigeon-hole, two such boxes, *A*, as have been described, one in possession of the box-subscriber and one in the pigeon-hole. Then, supposing the subscriber to have placed his mail 30 within his portable box at his office, and the box to have been locked by him and delivered to his carrier, the latter will convey it to the post-office. It becomes necessary now to have special means for the deposit of the mail within 35 the post-office. Accordingly we provide the inclined shelf or counter *C* and partition *P* with box-apertures *D* and the box stop or strip *S*. Arriving at the post-office, the carrier places the door end of the box in one of the apertures 40 *D* in an inclined position and allows it to remain until the post-office clerk has opened the door and the contents are discharged by gravity or by hand into a suitable receptacle. The door being then closed and spring-locked, the 45 carrier withdraws the empty box and proceeds with it to his box or pigeon-hole number, unlocks the outside lock, *a'*, of the box already in the pigeon-hole, withdraws it and inserts the locked box he had brought with him, which 50 he locks into its place by the lock *a'*; or, if a spring-lock is used, it locks itself into position. He then carries the second box, locked as he finds it, to his employer. At his convenience 55 the post-office-clerk unlocks the door of box last deposited, throws it open to the position shown in Fig. 2, and places the mail within. As the carrier withdraws the box from its pigeon-hole the door will be automatically closed as follows: When the box commences to move 60 the crank-lever *t* strikes the end of the side *F* of the pigeon-hole, causing a reaction by means of spring *s*, and the swinging of the door to the closed position, as shown in Fig. 6. For further assurance of locking the door there is a 65 further action by the lever *t* being further depressed in its passage through the pigeon-hole,

compressing the spring, and thus acting upon the door, as shown in Fig. 5.

There are other methods of closing the door which can be used in connection with our invention, and we have devised a box so arranged as not to require unlocking after the contents have been removed by the post-office clerk, having a slit into which the mail is inserted, and not requiring the automatic closing of the door, though this method necessitates more work on the part of the post-office delivery-clerk, and also makes an opening in the box.

The boxes *A* should have their ends *a* made 80 of metal, and they may be partially glazed and provided with metallic grate-bars at the outer ends, if desired.

In practice it will be desirable to cover the outer ends of the pigeon-hole partitions with 85 metal for greater security, as shown in Figs. 9 and 10 at *x*, and when that is done each portable box with a metallic end, *a*, locked in place in its pigeon-hole, will, together with the metal-covered walls of the pigeon-hole, form a complete metallic outer face, including each pigeon-hole and box; and a series of pigeon-holes and boxes locked in place within them will likewise present a continuous metallic front, in effect substantially the same, although the construction is different, for the purposes of security, 90 as that set forth in Reissued United States Letters Patent No. 8,783, July 1, 1879.

Instead of facing the front edges of the pigeon-hole walls with metal, a metal flange or projection, as shown at *y*, Figs. 11 and 12, may extend outward from all sides of the metallic end *a* of each portable box a distance equal to one-half the width of each pigeon-hole partition. This will serve to form a continuous metallic frontage when the boxes are all in place or locked in place in the pigeon-holes, and will also serve as a stop for the insertion of the boxes the proper distance to be locked.

Having thus described our invention, what 110 we claim, and desire to secure by Letters Patent, is—

1. A portable mail-box closed on all sides and at the outer end, and provided with a suitable fastening for securing the box in a pigeon-hole, and having a door at the inner end for the admission of mail-matter, substantially as described.

2. A portable mail-box closed at the outer end, and provided with a handle for withdrawing and carrying it, and having a door and a lock for fastening the door at the inner end, substantially as described.

3. In combination with a pigeon-hole or a series of pigeon-holes open at both ends, a portable supplemental mail-box or series of boxes, (each with a metallic front and with a door at its inner end,) secured removably within the same, forming a complete metallic facing or frontage, while open, for the reception of mail matter from within, substantially as described.

4. In combination with a pigeon-hole open at both ends, a portable mail-box provided with a door at its inner end hinged to the box and projecting so as to be struck by one of the partition-walls of the pigeon-hole, and closed by the act of withdrawing the box from the pigeon-hole, substantially as described.

5. The combination of the boss *g*, the bell-crank lever *t*, the door, the rod *p*, and the spring *s*, substantially as described.

6. The combination of an inclined shelf, an apertured partition, and a strip or stop, whereby a portable mail-box may be supported in an

inclined position for securely depositing its contents within a post-office, substantially as described.

In testimony whereof we have signed our names to this specification, in the presence of two subscribing witnesses, this 9th day of March, 1881.
